MELVIN L. STONE, OF LAWRENCE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed December 26, 1922. Serial No. 608,860.

To all whom it may concern:

Be it known that I, MELVIN L. STONE, a citizen of the United States, and a resident of Lawrence, in the county of Essex and State of Massachusetts, have invented an Improvement in Feeler Mechanisms for Looms, of which the following description, in connection with the accompanying drawings, is a specification, like characters on the drawings representing like parts.

This invention relates to feeler mechanisms for looms, whereby replenishment of filling is effected when that in the running shuttle reaches a condition of substantial exhaustion.

Feeler mechanisms of various types have heretofore been suggested, some of which have been well adapted for use in connection with one kind of filling, while other types have been better adapted to call the change in connection with other kinds of filling. It often happens, however, that in the same loom it may be desirable to employ filling of one kind for a time and then to use filling of a different kind, each being better adapted for use in connection with different types of feeler mechanism.

One of the objects of the present invention is to provide a feeler mechanism that may be converted readily from one type to another, as desired, or best adapted to the particular filling employed, without the necessity of changing the entire feeler mechanism or sacrificing the advantages incident to the use of the type of feeler mechanism best suited to the particular conditions. In its broader aspect, therefore, the present invention consists of a feeler mechanism that may be converted readily from one type to another by a simple and effective change in the relations of the parts of the same mechanism.

More specifically, the invention consists in a convertible "side swipe" and "penetrating" feeler mechanism wherein the feeler element may be rendered effective to call for replenishment of filling by side swipe action or movement in a direction longitudinally of the shuttle, or by filling penetrating pins which call the change of filling without side swipe movement of the feeler when they meet the more dense substance of the filling carrier or bobbin on a detecting heat.

The various novel features of the inven-

tion and new combination of parts will be made clear from the following description and accompanying drawing of one good practical form thereof, it being understood that many of the details may be changed within the true scope of the invention as defined by the claims.

In the drawings:

Fig. 1 is a perspective view of a loom containing the present invention, only sufficient parts of the loom being shown to make clear the association of the invention therewith;

Fig. 2 is a detached perspective view showing the rear end portion of the feeler mechanism;

Fig. 3 is a front to rear vertical section of the rear end portion of the feeler mechanism;

Fig. 4 is an enlarged top or plan view of the feeler mechanism with some of the overlying parts omitted for clearness of illustration and showing the mechanism adjusted to act as a "side swipe" feeler;

Fig. 5 is a view similar to that of Fig. 4 showing the parts adjusted to operate as a penetrating feeler; and

Fig. 6 is an enlarged perspective view with some of the parts broken away, showing details of construction.

The replenishing mechanism and details thereof are not herein shown and described because the details thereof form no essential parts of the present invention and moreover such mechanism is now well understood by those skilled in the art.

The loom frame 1 has secured thereto at each side a bracket 2 having a bearing 3 for the transverse or rock shaft 4 to which is secured the arm 5 extending upwardly from the rock shaft and pivotally connected at 6 to the lever 7, the front end 8 of which is adapted at times to be engaged by an operating member 9. The operating member 9 may be a part of or secured for movement with the weft hammer.

Between the lever 7 and the feeler mechanism proper is a transmitter which is adapted for operation when the filling is substantially exhausted to place the end 8 of the lever 7 in the path of the operating member 9 to call for a change of filling. In the present instance of the invention, the transmitter consists of a lever 10 pivotally

2
mounted on a stud 11 extending from a bracket 12*. The arm 12 of the transmitter carries a member 13 having cam portion, as 14, adapted to be engaged by the forward movement of an arm 15 which constitutes a part of the transmitter. The arm 15 is mounted for rocking movement on the stud 16 and is normally under the influence of a spring 17. The outer extremity of the arm 15 has a projection 18 which is adapted to be engaged by the actuator, presently to be described, when, on a detecting beat, the filling is substantially exhausted. The parts so far described are or may be of usual construction.

Extending outward from the loom frame is the shipper stand 19 from which projects a bracket 20 on which the feeler mechanism may be adjustably mounted by the bolt 21 passing through a slot 22, Fig. 1. In the present instance, the feeler stand 23 is mounted for adjustment rearwardly and forwardly of the loom and also laterally thereof, the former adjustment being possible through the slot 24 and pins 25 and the lateral adjustment being rendered by the bolts 26. These features for adjusting the feeler mechanism may be of usual construction.

30 The feeler mechanism of the present invention includes as part thereof a carrier which has a movement towards and from the front of the loom, and in the present instance the carrier 27 is formed as a slide, 35 as best indicated in Fig. 4, which is mounted in the feeler stand 23 for sliding movement towards and from the front of the loom, and is normally under the influence of a spring 28 for returning the carrier to its 40 rearward position. Suitable stops, such as 29, are provided to limit the movement of the carrier rearwardly. The carrier 27 may be of any known type now used, but the present invention is shown associated with a 45 carrier of the sliding type.

Pivotedly connected to the carrier 27 is the actuator 30. The pivotal connection of the actuator with the carrier is afforded by a pin 31 passing through the hub portion 32 of 50 the carrier and engaging the slide 27. Extending laterally, or off-set from the pivot 31 of the carrier is an arm 33 to which is pivotally connected at 34 the swinging rocker 35 which affords a convenient form of bearing for the front end portion 36 of pins 55 which are mounted on the feeler, as will presently appear.

The actuator has a small arm 37 projecting from the hub portion 32 thereof and 60 connected to such extension by the detachable screw 38 is the feeler 39.

The rear end portion of the carrier 27 is formed to support the feeler and actuator and the parts associated with each. In the 65 present instance, the rear portion 40 of the

carrier 27 has the upstanding side flanges 41 between which is mounted the feeler head 42 which is connected for rectilinear or side swipe movement by a projection or feather 43 which extends into the groove 44 formed in the rear portion of the carrier.

The feeler head 42 is loosely connected to the feeler 39 by a pin 45, as indicated in Fig. 6, the construction being such that lateral or side swipe movement of the feeler 39 will cause the feeler head 42 to move in a direction longitudinally of the shuttle by its engagement with the groove 44.

The feeler head 42 has mounted in it filling engaging pins, two being shown in the present instance of the invention, but the number may be varied. The feeler penetrating pins 36 pass through openings in the feeler head 42 and the filling engaging portions 46 extending beyond the head 42, while collars 47* on the pins limit the movement of the pins relative to the feeler in an outward direction.

The actuator 30 is normally under the influence of a spring 47 one end 48 of which acts upon the extension 37 from the hub of the actuator and the other end of which is secured to the pin 31, with the result that the actuator and the feeler when secured to the actuator as described, will be held in their normal position. A pin 49 extending through the slot 50 in the hub of the actuator serves to limit the extent of the movement permitted the actuator.

From the construction thus far described it will be apparent that when a working supply of filling is in the shuttle on a detecting beat, the outer portions of the pins 36 will directly engage the filling and sink into it and then the filling will engage the plane face at the rear end of the carrier 27 and by forward pressure thereon will move the carrier and the parts secured to it, in a forward direction, without, however, causing the actuator to call for a change of filling. When, however, the filling is substantially exhausted on a detecting beat the ends 46 of the pins will strike the more dense substance of the filling carrier or bobbin and be pushed forwardly thereby, causing the actuator 30 to be turned from its normal to its abnormal position and the feeler head 42 to be moved in a direction longitudinally of the shuttle. Should there be sufficient filling in the shuttle to continue weaving for a time it may obstruct the side swipe movement of the feeler head by engagement with the turned ends 46 of the pins and the replenishment of filling will be delayed for a time or until the filling is sufficiently exhausted to permit the pins to move in a direction longitudinally of the shuttle, whereupon the change will be called by the actuator as it moves forwardly under the forward pressure.

It will be noted from the construction thus far described that the pins which are carried by the feeder act upon the actuator and position the actuator to call for replenishment of filling when the feeder is free to move in a direction longitudinally of the shuttle, or in other words, when the pins themselves move along the filling carrier or bobbin as well as frontwardly relative to the feeder.

The side swipe feeler thus far described is specially adapted for use in certain looms or in connection with certain filling, but as hereinbefore pointed out, it may be desirable to convert the feeler from a side swipe to a truly penetrating type to accommodate the feeler action to a different loom or to a different kind of filling.

To this end the feeler 39 is detachably connected to the actuator and such detachable connection may be conveniently secured by the pin or screw 38 which passes through the extension 37 and into the feeler 39. When the feeler is thus connected to the actuator, it is substantially rigid therewith and moves with the actuator.

The feeler 39 has an opening 51, for the reception of a pin or lug to hold the feeler rigidly with the carrier 27 when it is detached from the actuator. In the present instance and for convenience of manipulation, the opening 51 in the feeler 39 is made of a size to receive the threaded pin 38, and directly beneath the opening 51 in the feeler 39 there is a threaded opening 52 formed in the carrier 27, the construction being such that when the pin 38 is removed from its position connecting the feeler and actuator and is passed through the opening 51 into the threaded opening 52 in the carrier, the feeler 39 becomes fixed, while the actuator still retains its freedom of action.

Under the conditions last described, that is, when the feeler 39 is disconnected from the actuator and secured in fixed position on the carrier 27, as indicated in Fig. 5, the feeler mechanism becomes one of the penetrating type without side swipe movement. In the construction last described, when a working supply of filling is present in the shuttle, the penetrating pins 36 sink into the filling substantially as before described. When, however, the filling is substantially exhausted on a detecting beat, the pins 36 are pushed frontwardly relatively to the feeler head and, acting upon the offset arm of the actuator, move the actuator into position to engage and operate the transmitter as the actuator is moved frontwardly. Thus the feeler mechanism may be employed either as a side swipe or penetrating feeler without side swipe movement by simple manipulation of parts of the feeler construction and without the introduction of any new or auxiliary parts.

Whether the feeler mechanism be employed as a side swipe feeler or merely a penetrating feeler without side swipe movement, it is desirable to prevent the feeler from calling the change of filling either by accidental movement of the feeler longitudinally of the shuttle in one case or the frontward movement of the pins which may meet a hard part of the filling in the other case.

To secure this result a lock is provided for the actuator and as shown comprises the plate 53, Fig. 3, pivotally mounted at 54 to lugs 55 rising from the rear portion of the carrier 27. The plate or arm 53 carries a pin 56 which is normally engaged with a part 57 formed in the hub 32 of the actuator. The arm or plate 53 also carries a rearwardly extending bunter 58 which, when the filling is approaching substantial exhaustion and the feeler enters further into the shuttle, strikes the front wall of the shuttle 59 as the lay beats up, thereby causing the pin 56 to be withdrawn from locking engagement with the actuator. The feeler is now free to call the change and will call the change when the filling reaches substantial exhaustion as hereinbefore described.

The shuttle 59 is of ordinary construction and carries the bobbin 60 having a supply of filling 61 thereon. The front wall of the shuttle is provided with an opening 62 and the front wall of the shuttle box is provided with an opening 63 so that the feeler may enter the shuttle on a detecting beat and perform its feeling function.

What is claimed is:

1. In a filling replenishing loom, a convertible side swipe and penetrating feeler mechanism, comprising, in combination, a carrier mounted for movement towards and from the front of the loom, a feeler on the carrier, an actuator having a normal stroke towards and from the front of the loom, filling penetrating pins carried by the feeler and engaging the actuator, and means for detachably connecting the feeler and actuator.

2. In a filling replenishing loom, a convertible side swipe and penetrating feeler mechanism, comprising, in combination, a carrier mounted for movement towards and from the front of the loom, a feeler mounted on the carrier, an actuator having an off-set pivotal connection with the carrier, filling penetrating pins mounted on the feeler and bearing at their front ends upon the actuator, and means for detachably connecting the feeler and actuator.

3. In a filling replenishing loom, a convertible side swipe and penetrating feeler mechanism, comprising, in combination, a carrier mounted for movement towards and from the front of the loom, a feeler mounted

105
110
115
120
125

130

on the carrier, an actuator having an off-set pivotal connection with the carrier, filling penetrating pins mounted on the feeler and bearing at their front ends upon the actuator, and means for detachably connecting the feeler and actuator, and an actuator lock which prevents movement of the actuator to its abnormal position until the filling reaches a predetermined degree of exhaustion.

4. In a filling replenishing loom, a convertible side-swipe and penetrating feeler mechanism, comprising a feeler which is mounted for movement in a direction longitudinally of the shuttle and held from such movement by the filling until substantial exhaustion thereof on a detecting beat, filling penetrating pins adapted to penetrate the filling on detecting beats and engage the more dense surface of the filling carrier and be moved frontwardly thereby when the filling is substantially exhausted, an actuator, and means for selectively rendering the actuator operative to effect replenishment of filling by side-swipe movement of the feeler or frontward movement of the penetrating pins when filling is substantially exhausted on a detecting beat.

5. In a filling replenishing loom, a convertible side-swipe and penetrating feeler mechanism, comprising, in combination, a feeler mounted for movement in a direction longitudinally of the shuttle to call for a change of filling, a penetrating member adapted to penetrate the filling on a detecting beat and be moved frontwardly relative to the feeler when the filling is substantially exhausted, an actuator, and means for rendering the actuator operative to effect replenishment of filling either by movement of the feeler longitudinally of the shuttle or by frontward movement of the penetrating members.

6. In a feeler mechanism for looms, the combination of a carrier mounted for movement towards and from the front of the loom, an actuator mounted on the carrier and having movements with and independently of the carrier, a feeler having pins which penetrate the filling on a detecting beat, an arm extending from the actuator against which the front end portion of the pins bear, means for interchangeably connecting the feeler to the actuator and carrier that the feeler mechanism may be readily converted from a side swipe to a penetrating feeler, and a transmitter which is

actuated by the actuator for replenishing the filling.

7. A feeler mechanism for looms, comprising a feeler having pins movable relative to the feeler and directly meeting the filling on a detecting beat and displaced frontwardly by the contact pressure when the filling is substantially exhausted, an actuator detachably connected to the feeler and having a reciprocating stroke towards and from the front of the loom, an off-set portion carried by the actuator and engaging the front portions of said pins, and a transmitter which is actuated by the actuator in the frontward stroke thereof when the pins have been moved frontwardly relative to the feeler, and a lock which locks the pins from frontward movement relative to the feeler by the frontward pressure until the filling has reached a predetermined degree of exhaustion.

8. A feeler mechanism for looms, comprising a carrier, a feeler having pins movable relative to the feeler and directly meeting the filling on a detecting beat and displaced frontwardly by the contact pressure when the filling is substantially exhausted, an actuator having a normal reciprocating stroke towards and from the front of the loom, a part carried by the actuator and engaged by the pins, means for securing the feeler to the actuator to have side swipe movement therewith and permit the pins to be moved frontwardly relative to the feeler as the feeler side swipes and to be detached from the actuator and secured to the carrier to cause the frontward movement of the pins by the frontward pressure to abnormally displace the actuator.

9. A convertible side swipe and penetrating feeler mechanism, comprising, a carrier, an actuator pivotally mounted on the carrier, a feeler detachably connected to the actuator and having a head restrained to movement longitudinally of the shuttle relative to the carrier, means for locking the feeler head from such movement when the feeler is detached from the actuator, an arm on the actuator off-set from the pivot of the actuator, pins carried by the head and bearing against said off-set arm, and a transmitter operated by the actuator in its frontward stroke when the pins have been moved frontwardly by the frontward pressure.

In testimony whereof, I have signed my name to this specification.

MELVIN L. STONE.
